UNITED STATES PATENT OFFICE.

JOSEPHINE POMEROY HERRICK, OF CLEVELAND, OHIO.

PAIL-SUPPORTING TRUCK.

Application filed March 31, 1925. Serial No. 19,658.

To all whom it may concern:

Be it known that I, JOSEPHINE P. HERRICK, a citizen of the United States, and a resident of Cleveland, in the county of 5 Cuyahoga and State of Ohio, have invented a new and Improved Pail-Supporting Truck, of which the following is a full, clear, and exact description.

This invention relates to pail supporting 10 trucks and more specifically to an apparatus which constitutes a wheeled truck or carriage and which is adapted to support a pail or bucket and permit the latter to be moved from place to place without the 15 necessity of lifting the pail.

An object of the invention is therefore 20 to provide a truck which conveniently supports a pail or bucket, holding the same against lateral displacement and permitting the same to be rolled over the floor from place to place so as to avoid the necessity 25 of lifting and depositing a heavy pail, full or partially full of water, and therefore resulting in a labor saving device as well as one which saves time and provides convenient means for moving the pail about.

A further object is to provide a truck or carriage of this kind which is of extremely 30 simple, inexpensive construction, which adds but little weight to the pail when it is desired to manually lift the pail and carry it.

With these and other objects in view, the 35 invention consists in certain novel features of construction and combinations and arrangements of parts, which will be more fully hereinafter described and pointed out in the claims.

Figure 1 is a view in longitudinal section 40 illustrating my improved truck with a pail in position thereon;

Figure 2 is a view in end elevation;

Figure 3 is a top plan view;

Figure 4 is a plan view of the blank 45 from which the wire netting frame is made.

A represents my improved truck, which comprises a platform 1 supported by rollers or wheels 2. I have illustrated as rollers or wheels ordinary casters, which may be 50 connected to the platform in any approved manner, and I may employ any desired number of these casters to properly support the platform and give a wheel mount therefor.

On the platform 1 I secure a frame 3. 55 This frame 3 preferably comprises a sheet or

blank of wire netting, such as illustrated in Figure 4, having its ends cut out or recessed as shown at 4 and folded on the lines 5, 6, 7 and 8, to provide a basket-like frame which is rigidly secured to the platform 1 by any suitable devices, such as indicated at 9.

The recesses 4 are of such a size and are sufficiently spaced to accommodate a pail 10 between them and to allow the pail to rest 65 on the netting which is secured to the platform.

The pail projects preferably above the frame-work 3 and is provided with an ordinary handle 11, while flexible supports 70 12, preferably chains, are secured at their ends to the sides of the platform and are of such a length as to provide loops or bails to form handles and to allow the device as a whole to be lifted and transported from 75 place to place.

It will be noted that there is sufficient 80 space under the netting framework at both sides of the pail 10 to accommodate brushes, soap and other articles so that the latter 85 are within convenient reach for use when desired.

This device permits a pail filled with water, and which is necessarily heavy, to be 85 moved from place to place during the scrubbing or cleaning operation, and relieves the operator of the laborious task of lifting the pail as she moves about in doing her work.

Various slight changes and alterations 90 might be made in the general form of the parts described without departing from the invention, and hence I do not limit myself to the precise details set forth but consider myself at liberty to make such slight changes 95 and alterations as fairly fall within the spirit and scope of the appended claims.

I claim:

1. A device of the character described, 100 comprising a wheeled platform, a frame secured on the platform and comprising a sheet having its intermediate portion secured directly to the platform and its ends projected upwardly and then inwardly, the extremities of said sheet being curved 105 whereby an opening is formed to receive a pail when the latter is positioned on the platform.

2. A device of the character described, 110 comprising a wheeled platform, a frame secured on the platform and comprising a sheet having its intermediate portion se-

cured directly to the platform and its ends projected upwardly and then inwardly, the extremities of said sheet being curved whereby an opening is formed to receive a pail when the latter is positioned on the platform, said frame being open at the sides of the device whereby entrance for articles on to the platform at opposite sides of the pail is provided.

10 3. A device of the character described, comprising a wheeled platform, a frame secured on the platform and comprising a

sheet having its intermediate portion secured directly to the platform and its ends projected upwardly and then inwardly, the extremities of said sheet being curved whereby an opening is formed to receive a pail when the latter is positioned on the platform, and a pair of flexible handles secured at their ends to the platform and at their intermediate portions extending above the frame.

(Mrs.) JOSEPHINE POMEROY HERRICK.
